UNITED STATES PATENT OFFICE.

CARL J. MITISKA, OF HOWELL, INDIANA.

STOVE.

1,390,151.

Specification of Letters Patent. Patented Sept. 6, 1921.

Application filed May 21, 1920. Serial No. 383,278.

To all whom it may concern:

Be it known that I, CARL J. MITISKA, a citizen of the United States, residing at Howell, in the county of Vanderburg and 5 State of Indiana, have invented a new and useful Stove, of which the following is a specification.

This invention relates to heating stoves.

The object is to provide a stove of this 10 character wherein fresh air is taken through the top of the stove, under damper control, and passed interiorly of the stove through the products of combustion, becoming highly heated, and introduced over the bed of coals 15 within the firepot, mingling with the flames and the smoke to produce intense heat, thus resulting in economy of fuel and a greater heat radiation than in ordinary stoves.

A full and complete understanding of 20 the invention may be obtained from a consideration of the following detailed description taken in connection with the accompanying drawing forming part of this application with the understanding, however, that 25 the invention is not confined to any strict conformity with the showing of the drawing, but may be changed and modified, so long as such changes and modifications mark no material departure from the salient features of the invention as expressed in the appended claims.

In the drawing, in which similar reference characters designate corresponding parts throughout the several figures,

30 Figure 1 is a vertical sectional view through the improved stove, the section being taken through the doors thereof;

Fig. 2 is a similar sectional view taken at right angles to Fig. 1;

Fig. 3 is a top plan view, partly in section;

Fig. 4 is a detail perspective view of the water container to be used in connection with the stove.

45 In stoves of the class to which the present invention relates, the object sought has been to furnish a continuous supply of fresh air directly over the fire bed in order that a sufficient quantity of oxygen may be present 50 to produce proper heat. This has ordinarily been done by conducting the fresh air from the sides of the stoves, thus necessitating the use of short flues or conduits which, while supplying the necessary amount of fresh air, 55 conducted or deposited the same over the

fire in a relatively cold condition, thus acting not only to retard combustion but to reduce the amount of heat radiated by the stove.

The present invention contemplates the 60 employment of relatively long air conducting flues or conduits extending from the top of the stove, almost throughout the entire length of the same and on the interior thereof, to a point directly over and around the 65 margins of the fire box, the air during such extended passage, becoming thoroughly heated and finding exit during its route through a plurality of ports which serve to deposit the air at increasing temperatures 70 into the flames and heat during its downward passage until the lowermost exit is reached directly at the margin of the fire box.

The stove comprises the drum or casing 1, which may be formed of a tubular casting 75 of appropriate metal or it may be constructed of suitable heavy sheet metal forming a cylindrical casing of any desired dimensions. This drum is supported upon a fire pot 2 in any desired manner, said fire pot, 80 in turn, resting upon a base member 3, preferably rectangular in form. An ash pit 4 is provided having the usual door 5. Base member 3 is adapted to be supported upon ordinary stove legs 6. A grate 7 is located 85 as usual at the lower part of the fire pot, and the latter may be lined with fire brick as indicated in dotted lines at 8. All the above is of the ordinary construction and may be varied as desired.

Located a relatively short distance below the top circumferential edge of the drum 1, a stationary or permanent head 9 is suitably secured, said head being imperforate and forming a tight closure for the upper 95 end of the drum. An upstanding tube 10 communicates with the interior of the drum adjacent to the rear thereof and extends somewhat above the upper edge of the same, the said tube being preferably oval in cross 100 section and provided with a port or orifice 11, just above the head 9, for a purpose to be described.

A removable head or cover 12 is adapted to rest upon the upper edge of the drum 1, 105 and is provided with a downwardly extending flange 13 in surrounding relation to the drum, and forms an air-tight closure therefor, the cover 12 being provided with a corresponding up-standing tube 14 capable of 110

sliding over and surrounding the first-named tube 10, and forming a suitable connection for the usual smoke pipe 15.

The space confined between the two heads 5 9 and 12 respectively forms an air distributing chamber 16, communication with which is had with the atmosphere through the medium of a damper plate 17, preferably of circular formation, and centrally 10 pivoted to a closure plate or lid 18, having a depending flange fitting within a corresponding opening formed at the center of the cover 12. The lid 18 which is readily removable from its seat in the cover 12, is 15 provided with a series of openings arranged circumferentially around the pivot of the same, and adapted to be uncovered by a corresponding series of openings or apertures 19 formed in the damper plate 17 in the usual manner, a greater or lesser amount of opening being readily obtainable by reason of the registering relation of the said openings, the damper plate being adapted to be 20 swung about its pivot by means of a suitable handle 20.

A series of air conduits or flues 21 formed of suitable metal and comprising three sides of a rectangle, are adapted to be secured to the interior walls of the drum 1 as by bolts 30 22, said flues 21 having their upper open ends communicating with the air distributing chamber 16, and their lower open ends located at the lower end of the said drum 1 in close proximity to the upper ends of 35 the fire bricks.

The conduits 21, which may be of any other form in cross section, are provided along their opposite side walls with a series of outlets 23, which serve to distribute the 40 heated fresh air directly over the fire, the same being drawn through the conduits 21 by reason of the upward draft of the products of combustion through the smoke pipe 15.

45 A bake oven 24, preferably rectangular in cross section, comprising side walls, a top and bottom wall, and a rear wall 25 located in spaced relation to the rear wall of the drum 1, is suitably supported over the fire pot, a short distance below the permanent head 9. The oven is open at the front of the drum 1, and is adapted to be closed by a suitably hinged door 25^a which may be swung down to form a shelf when open.

50 Located a short distance below the bottom wall of the oven 24 there is formed a baffle plate 26, preferably integral with the oven and extending to the rear edge thereof. The baffle plate is connected to the bottom of the oven by side walls co-extensive therewith, and the space confined between the same constitutes a cold air passage, open at the front and rear ends and controlled by a suitable slide damper 27 of ordinary construction. The rear end of the cold air

passage is in spaced relation to the rear wall of the drum so that the air passing therethrough may find ready outlet to intermingle with the heat and pass up the smoke pipe 15.

70 The fuel feed door 28 is located immediately below the damper 27 in the usual location at the front of the drum 1, and it will be seen the several operable parts are within easy reach.

75 In Fig. 4 of the drawing there is illustrated a removable water heating reservoir 29 made of suitable metal, and in the form of a tight rectangular box of the proper dimensions to easily slide into the bake oven 80 24, after the door 25^a is removed from its hinges for the purpose.

85 The water reservoir is provided with an opening 30 in its top wall, and has a filling opening 31 in its front wall surrounded by a guard 32 to facilitate the pouring of water into the same, and a faucet 33 located at the bottom of the front wall in order that hot water may be drawn off when desired.

90 The port 11, which is open at all times and connects the chamber 16 with the smoke pipe 15 serves, when lighting a fire in the stove, to draw off and up the pipe 15 all smoke and gases which may arise through the conduits 21 and otherwise escape into the 95 room, the draft being sufficient to overcome such tendency.

95 From the foregoing it will be seen that a simple, cheaply manufactured and easily operated heating stove has been provided, 100 which, by reason of the conduits 21, will operate to distribute super-heated fresh air directly over the fire to the best advantage to secure intense heat from the combustion with great economy in the consumption of fuel. 105

In a divisional application filed Jan. 13, 1921, Serial No. 437026, I have claimed the oven and heat regulating means therefor.

What is claimed is:

1. A stove comprising a fire pot, a drum 110 mounted above the fire pot, an air chamber provided at the top of the drum, damper-controlled means connecting the air chamber with the exterior of the stove so as to supply said chamber with fresh air, and 115 vertically disposed conduits arranged around the interior walls of the drum and communicating at their upper ends with the air chamber and at their lower ends with the fire pot, said conduits being provided with 120 a plurality of air outlets in their side walls located at different points of the conduits.

2. A stove comprising a fire pot, a drum mounted above the fire pot, a removable cover adapted to engage the upper edge of 125 the drum and form an airtight closure therefor, a stationary head spaced below the removable cover to provide an intervening air chamber, and vertically-disposed conduits arranged around the interior walls of the 130

drum and communicating at their upper ends with the air chamber and at their lower ends with the upper portion of the fire pot, said conduits being provided with a plurality of air outlets, said outlets being disposed at different points along the conduits.

3. A stove comprising a firepot, a drum mounted on the firepot, an air chamber provided at the top of said drum, damper controlled means connecting the air chamber with the exterior of the stove, and vertically-disposed conduits arranged around the interior walls of the drum and communicat-

ing at their upper ends with the air chamber and at their lower ends with the firepot 15 and provided with a plurality of spaced air outlets in their side walls, said conduits being formed by trough-like members and a portion of the wall of the drum inclosed by said members, said trough-like members being secured to the wall of the drum. 20

In testimony that I claim the foregoing as my own I have hereto affixed my signature.

CARL J. MITISKA.
